UNITED STATES PATENT OFFICE.

GILBERT THORSEN, OF LETCHER, SOUTH DAKOTA.

CYLINDER-TOOTH WRENCH FOR THRESHING-MACHINES.

SPECIFICATION forming part of Letters Patent No. 667,044, dated January 29, 1901.

Application filed May 11, 1900. Serial No. 16,347. (No model.)

To all whom it may concern:

Be it known that I, GILBERT THORSEN, a citizen of the United States, residing at Letcher, in the county of Sanborn and State of South Dakota, have invented a new and useful Cylinder-Tooth Wrench for Threshing-Machines, of which the following is a specification.

The invention relates to improvements in cylinder-tooth wrenches for threshing-machines.

One object of the present invention is to improve the construction of wrenches for operating on the cylinder-teeth of threshing-machines and to provide a simple and comparatively inexpensive one adapted to be readily clamped to the cylinder-bar and capable of operating on the teeth thereof without obstructing the view of the operator.

A further object of the invention is to provide a wrench of this kind adapted, after being positioned on the cylinder-bar, to be readily operated with one hand, so that the tooth may be tapped by a hammer in the other hand of the operator, whereby a tooth may be firmly set in a minimum amount of time.

The invention consists in the construction and novel combination and arrangement of parts hereinafter fully described, illustrated in the accompanying drawings, and pointed out in the claims hereto appended.

In the drawings, Figure 1 is a perspective view of a wrench constructed in accordance with this invention. Fig. 2 is a longitudinal sectional view of the same. Fig. 3 is a transverse sectional view of one end of the wrench. Fig. 4 is a similar view of the other end of the wrench.

Like numerals of reference designate corresponding parts in all the figures of the drawings.

1 designates a frame or stock provided with a tubular portion 2 and having a hollow arm 3 extending from one end thereof and adapted to receive spur-gearing for communicating motion from a longitudinal shaft 4 to a rotary wrench-head 5, arranged parallel with the shaft 4 and extending inward from the outer end of the arm 3, which is arranged at right angles to the tubular portion 2. The ends of the arm 3 are bifurcated and receive spur gear-wheels 6 and 7, which are fixed to reduced portions 8 and 9 of the longitudinal

shaft 4 and the wrench-head 5 and which mesh with an intermediate gear-wheel or pinion 10, mounted on a suitable shaft 11 and arranged at the center of the arm to change the direction of the rotation of the wrench-head, so that the latter will rotate in the same direction as the shaft 4. The reduced portion 9 of the wrench-head consists of a stem, and the gear-wheels of the shaft 4 and the wrench-head may be keyed or otherwise secured to such parts. The other end of the longitudinal shaft 4 receives a ratchet-wheel 12, which is adapted to be engaged by either of a pair of spring-pressed pawls or dogs 16 and 17, pivoted between their ends in the bifurcated inner end 18 of an operating-handle 19 and having a spring 20 interposed between their inner ends and adapted to throw their outer, engaging ends into engagement with the ratchet-wheel when the pawls or dogs are free to move in such direction. The pawls or dogs are adapted to permit the shaft to be rotated continuously in either direction by the oscillation of the handle, and they are controlled by an adjustable ring 21, having a projecting portion or flange 22, adapted to be engaged with the inner end of either of the pawls or dogs to swing the outer end of such pawl or dog out of engagement with the ratchet-wheel. The bifurcated end of the operating-arm is perforated for the reception of the adjacent end 23 of the shaft 4, which is reduced, as shown, and which has a knob or head 25 secured to it and arranged at the outer face of the said bifurcated end of the operating-arm.

The operating-arm is composed of inner and outer sections 26 and 27. The outer or handle portion of the arm has its inner end 28 grooved and bifurcated to receive an arm or extension 29 of the inner section, and the said arm or extension 29 is provided with a web 30, which is secured in the groove and bifurcation by a transverse pivot 31, passing through both of the sections 26 and 27. The arm 29 is provided at its outer end with a shouldered notch 32, preferably formed in the web 30 and engaged by a beveled spring-actuated bolt 33, which is adapted to lock the outer section rigid with the inner section. The pivoted joint between the inner and outer sections of the operating-handle permits the

outer section to fold compactly against the body portion or stock and to be arranged at an angle to the inner portion should it be more convenient to oscillate in such position.

- 5 The tubular portion of the body or stock is provided with a longitudinal way 34, consisting of a flat longitudinal portion projecting laterally from opposite sides of the tubular portion and forming flanges to receive a slide 10 35, which has corresponding side flanges, substantially L-shaped in cross-section, to engage the flanges of the ways or guide. The slide is provided with an outwardly-extending ring 36, and it has longitudinal arms 37 and 15 38, between which is journaled a toothed head 39 of a lever 40. The head 39 of the lever 40 is provided with corrugations or grooves to form teeth 42, which are adapted to mesh with a rack 43, consisting of transverse teeth and 20 located at one end of the guide or way 34. When the lever 40 is oscillated, the teeth of its head 39 are caused to mesh with the teeth of the rack 43, and the slide is reciprocated to carry a rotary jaw or holder 44 toward and 25 from the wrench-head. One of the arms of the slide is provided with ratchet-teeth 45, which are engaged by a spring-actuated dog or detent 46, mounted on the lever 40 and adapted to be operated by a latch-lever 47. 30 The latch-lever 47 is pivoted in a bifurcation 48 of the handle of the lever 40, and it is connected with the dog or detent 46 by a rod 49, on which is disposed a spring 50, which is interposed between the dog or detent 46 and a 35 suitable stop on the lever, whereby the dog or detent is held in engagement with the ratchet of the arm 37.
- The ring 36 of the slide forms a bearing for the jaw or holder 44, which is adapted to turn 40 therein, and the said jaw or holder is provided with a slot 51 to receive the tooth to be operated on. The tooth is placed in the slot or opening of the jaw or holder, and the wrench-head is arranged at the inner end of the tooth 45 at the inner face of the cylinder-bar in position to engage the nut. The lever 40 is then oscillated to engage the jaw or holder with the outer portion of the tooth, and to bring the wrench-head in proper position, and by 50 this construction the device will be held on the cylinder-bar so that it may be operated with one hand, thereby permitting the other hand of the operator to be employed for tapping the tooth with a hammer to cause it to be firmly seated. The toothed head of the lever 40 is adapted to be swung clear of the teeth of the rack to permit it to be brought to any point on the latter to adapt it to the cylinder and tooth to be operated on. 55
- 60 It will be seen that the wrench is simple and comparatively inexpensive in construction, that it is easily operated by one hand to screw a nut on or off a tooth, and that it is adapted to retain itself in proper position. 65 It will also be apparent that the wrench is adapted to be operated with the work turned toward the operator, so that he may see the

same during the operation of screwing a nut on or off the threaded end or shank of a tooth. Furthermore, it will be apparent that the wrench-head is adapted to hold the nut, and that the latter will be prevented from dropping into a separator in removing it from a tooth.

What is claimed is—

1. A device of the class described comprising a stock or body having a guide or way and provided with a rack, a wrench-head journaled on the body, gearing for operating the wrench-head, a slide mounted on the guide or way and having a jaw or holder located opposite the wrench-head, a lever mounted on the slide and having a toothed head engaging the rack and adapted to advance the slide, and means for locking the lever, substantially as described. 75

2. A device of the class described comprising a stock or body, a rotary wrench-head, gearing for operating the wrench-head, a rack, a slide mounted on the body and having a jaw or holder located opposite the wrench-head, a lever mounted on the slide and having a toothed portion adapted to mesh with the rack and to be swung out of engagement with the same, and means for locking the lever, substantially as described. 80

3. A device of the class described comprising a stock or body having a guide and provided with a rack, a rotary wrench-head, gearing for operating the same, a slide mounted on the guide and having a jaw or holder arranged opposite the wrench-head, said slide being provided with arms and having a ratchet on one of the same, a lever mounted between the arms and having a toothed head arranged to mesh with the rack, and a dog or detent carried by the lever and engaging the ratchet, substantially as described. 105

4. A device of the class described comprising a stock or body, a wrench-head mounted on the stock or body, gearing for operating the wrench-head, a slide mounted on the stock or body and provided with a bearing extending outward and located opposite the wrench-head, a rotary jaw or holder journaled in the bearing, and means for operating and for locking the slide, substantially as described. 110

5. A device of the class described comprising a stock or body having a longitudinal tubular portion and provided at one end thereof with an arm, a shaft extending through the tubular portion, a wrench-head mounted on the arm, gearing located within the arm and connecting the wrench-head with the shaft at one end thereof, a ratchet-wheel mounted on the shaft at the other end of the same, an operating-arm provided with pawls or dogs for engaging the ratchet-wheel, and a slide mounted on the tubular portion of the stock or body and located between the arm and the wrench-head and provided with a jaw or holder, substantially as described. 120

6. A device of the class described comprising a stock or body having a tubular portion

and provided at one end thereof with an arm, a shaft passing through the tubular portion, a wrench-head mounted on the arm, gearing connecting the wrench-head with the shaft at one end of the latter, a ratchet-wheel mounted on the other end of the shaft, an oscillating arm composed of two sections pivoted together, one of the sections being provided with an arm overlapping the other section, means for locking the sections rigidly together, and pawls or dogs carried by the arm for engaging the ratchet-wheel, substantially as described.

7. A device of the class described comprising a stock or body provided at one end with an arm, a longitudinal shaft journaled in the stock or body, a wrench-head mounted on the arm, gearing connecting the wrench-head with

the adjacent end of the shaft, a ratchet-wheel mounted on the other end of the shaft, an arm composed of two sections pivoted together and provided with means for locking them rigid with each other, pawls mounted on the arm for engaging the ratchet-wheel, and a slide guided on the stock or body and located between the arm and the wrench-head, and provided with a jaw or shoulder, substantially as described.

In testimony that I claim the foregoing as my own I have hereto affixed my signature in the presence of two witnesses.

GILBERT THORSEN.
